HEAT DETECTOR

Leo Francis Obermeyer and Edward C.
Obermeyer, Grand Rapids, Mich.

Application May 23, 1944, Serial No. 536,936

7 Claims. (Cl. 200—137)

This invention aims to provide a circuit maker and breaker adapted primarily but not exclusively to operate a signal, responsive to an abrupt rise of temperature, the device being unresponsive to a slow temperature rise, adjustment being possible, to the end that operation may take place at different speeds of temperature rise.

Within the scope of what is claimed, the structure described and shown may be changed, without departing from the spirit of the invention.

In the drawings:

Figure 1 shows in perspective, a device constructed in accordance with the invention;

Figure 2 is a side elevation, parts being broken away;

Figure 3 is a bottom plan;

Figure 4 is a rear elevation wherein the back of the casing has been removed;

Figures 5 and 6 are sections taken longitudinally of the device, one thermostatic element and associated parts being shown in one of the views specified, and the oppositely-disposed thermostatic element and associated parts being shown in the other of said views; and

Figure 7 is a circuit diagram.

In carrying out the invention, there is provided a support 1, which, preferably, is an elongated, box-like casing, made of material which is a non-conductor of electricity, the material being weather-proof, to the end that it may not warp and alter the relative positions of the somewhat delicate parts which it houses. The support 1 is supplied with any desired number of air-admission openings 2, disposed as desired, the support having a hole 3, shown in Figs. 2 and 6, the purpose of which will be made manifest hereinafter.

Within the casing 1 is disposed a longitudinal arm 4 and a longitudinal arm 5, arranged in approximately parallel relation. A binding post 6 secures one end of the arm 4 to one end wall of the casing 1, a binding post 7 exercising a like office with respect to the arm 5. The arms 4 and 5 are made of material which is responsive to heat and a conductor of electricity, metal being preferred.

The arms 4 and 5 extend practically the entire length of the casing 1, the arm 4 being equipped with a laterally and outwardly inclined foot 8, adapted to be engaged by an adjusting device, such as a transverse screw 9, threaded into the casing 1, the screw having a turning head 10, carrying an index 11 adapted to cooperate with a dial 12 on the casing 1.

The arm 5 is provided with an outwardly extended foot 14, which bears against a cam 15 on

a transverse shaft 16, journaled in a bearing block 17 in the casing 1. The shaft 16 has a head 18, provided with a screw driver kerf 19 accessible through the hole 3 in the casing 1.

5 The numeral 20 marks an inwardly bowed thermostatic element, having its ends secured at 21 to the arm 4. The numeral 22 designates an inwardly bowed thermostatic element having its ends secured at 23 to the arm 5. In length, the 10 thermostatic elements 20 and 22 approximate, respectively, the lengths of the arms 4 and 5.

At their place of closest approach to each other, the thermostatic elements 20 and 22 are supplied, respectively, with a contact 24 and with a contact 15 25. The thermostatic elements 24 and 25 are adapted to be brought into engagement, but they are a little off-center, so far as a horizontal axis is concerned. This causes the thermostatic elements 24 and 25 to have a wiping engagement, and they 20 remain always clean and bright.

The thermostatic elements 20 and 22 are conductors of both heat and electricity. The arms 4 and 5 respond somewhat slowly to heat, so far as the expansion of those parts are concerned. The 25 thermostatic elements 20 and 22 respond more rapidly to heat. The operation under consideration may be brought about by giving the thermostatic elements 20 and 22 a cross section which is markedly less than the cross section of the 30 thermostatic elements 4 and 5. It will be noted that, since the arms 4 and 5 are secured only by the binding posts 6 and 7, at one end, to the casing 1, the arms may expand in the direction of their length. The thermostatic elements 20 and 35 22, however, are secured, respectively, at 21 and 23, to the arms 4 and 5, respectively, and, therefore, heat will cause the thermostatic elements to bow inwardly and bring the contact projections 24 and 25 into engagement.

40 The numeral 26 designates a ribbon-like conductor of practically the same length as the casing 1. The conductor 26 is of approximately the same cross section as the thermostatic elements 20 and 22, and, therefore, is a member which responds

45 quickly to heat, so far as expansion and contraction are concerned, the part 26 being a conductor of electricity. The part 26 has a transverse end 27, bound between the upper end of the arm 4 and the upper end wall of the casing 1 and in electrical contact with the arm 4. The 50 lower end of the conductor 26 is free, and the conductor tends to expand in the direction of its length. At its lower end, the conductor 26 has a lateral foot 28.

The foot 28 of the conductor 26 is adapted to

engage an adjustable contact, preferably in the form of a screw 29, threaded into the lower end wall of the casing 1. The screw 29 has an external turning head 30, carrying an index 39 adapted to cooperate with a dial 31 on the lower end wall of the casing 1. It may be remarked at this place that such terms as "lower" and "upper" are selected merely for convenience in description. The device may be mounted otherwise than in the upper position depicted in Fig. 1.

The screw 29 is threaded through an angular conducting strip 32, one portion of which extends along the lower end wall of the casing 1, the other portion of the strip extending upwardly along the surface of the bearing block 17. The shaft 16 is in engagement with the upright portion of the strip 32 and the strip, therefore, forms a link, electrically considered, between the screw 29 and the cam 15 on the shaft 16.

The binding post 6 is joined by a conductor 33 to one side of a source 34 of electrical energy. The opposite side of the source 34 is joined by a conductor 35 to a signal 36, which may be either audible or visible. A conductor 37 joins the signal 36 electrically to the binding post 7.

By means of the shaft 16 and the cam 15, the arm 5 is operated to give an average position for the contact 25, and the position of the contact 24, relatively to the contact 25, is determined by operating the arm 4, through the instrumentality of the screw 9.

When the temperature rises slowly, the thermostatic elements 20 and 22 tend to bow toward each other, but there is sufficient time for the arms 4 and 6 to become heated, and expand longitudinally, the contacts 24 and 25 being spaced apart in a direction parallel to the arms 4 and 5. The signal circuit remains open, and the signal 36 is not operated. Such an operation takes place during ordinary temperature changes in the space wherein the device is located.

In the event of a rapid rise of temperature, such as may take place in the instance of conflagration, the thermostatic elements 20 and 22 respond to the temperature rise, and bring the contacts 24 and 25 into engagement before the arms 4 and 5 have had time to expand longitudinally and separate the contacts in a direction parallel to the arms. The signal circuit is closed, and the signal 36 operates.

The arms 4 and 5 ultimately respond to the rapid rise of temperature, and separate the contacts 24 and 25, in a direction parallel to the arms 4 and 5; but the signal 36 continues to operate, because the thermostatic element 26, which acts quickly, like the thermostatic elements 20 and 22, has come into engagement with the screw 29.

When the thermostatic element 26 touches the screw 29, there is established a signal circuit comprising the source 34, the conductor 33, the binding post 6, the thermostatic element 26, the screw 29, the strip or bracket 32, the shaft 16, the cam 15, the arm 5, the binding post 7, the conductor 37, the signal 36, and the conductor 35.

By swinging the arm 4 inwardly, or letting it spring outwardly, as dictated by the position of the screw 9, the space between the contacts 24 and 25 may be varied, thus setting the machine to operate responsive to various speeds of temperature rise.

The screw 29 may be advanced or retracted with respect to the foot 28 of the conductor or thermostatic element 26, and the machine may be set as to operate at a selected temperature, the

position of the index 39 with respect to the scale or dial 31 having been noted.

The thermostatic elements 20 and 22 are carried, respectively, by the arms 4 and 5 and are expansible transversely of the arms. The contacts 24 and 25 are convexed buttons, which are slightly off center, transversely of the arms. The cam 15 and the screw 9 are adjusting devices engaging the arms 5 and 4, respectively, the cam 15 being so mounted on the casing 1 that the cam affects gross adjustment of the arm 5, whereas the screw 9 effects a fine adjustment of the arm 4.

The strip 26 and the screw 29 constitute a normally-open thermostatic switch interposed in the signal circuit, the sensitivity of the switch to heat being approximately the same as that of the members 20 and 22. The screw 29 and the strip 26 form relatively-movable switch-parts, the screw being under the control of an operator, thereby to vary the space between the screw and the said strip and to predetermine the time-interval between the spacing of the contacts and the closing of the switch.

What is claimed is:

1. A circuit maker and breaker comprising a support, thermostatic arms having their corresponding ends secured to the support, the opposite ends of the arms being free, to provide for the longitudinal expansion of the arms, thermostatic elements carried by the arms and expansible transversely of the arms, contacts carried by the thermostatic elements, and means for bringing the arms into an electrical circuit to be opened and closed, the thermostatic elements being more quickly responsive to heat than are the arms, whereby the contacts will close together before the arms have time to expand longitudinally and space the contacts.

2. A circuit maker and breaker constructed as set forth in claim 1, and wherein the thermostatic elements are strips bowed toward each other, each strip being secured at both ends to one of the arms, the strips extending longitudinally of the arms.

3. A circuit maker and breaker constructed as set forth in claim 1, and wherein the thermostatic elements are strips bowed toward each other, each strip being secured at both ends to one of the arms, the strips extending longitudinally of the arms, and contacts on the strips near the place where the strips approach each other most closely, the contacts being convexed and slightly off center, transversely of the strips, whereby the contacts will have a wiping contact with each other.

4. A circuit maker and breaker constructed as set forth in claim 1, in combination with an adjusting means mounted on the support and engaged with one arm, to vary the space between the contacts.

5. A circuit maker and breaker constructed as set forth in claim 1, in combination with adjusting devices engaging the respective arms, to vary the space between the contacts, means for mounting one of said devices on the support for gross adjustment, and means for mounting the other of said devices on the support for fine adjustment.

6. A circuit maker and breaker constructed as set forth in claim 1, in combination with a normally-open thermostatic switch carried by the support, and interposed in the circuit to be opened and closed, the switch constituting means for closing said circuit after the arms have expanded longitudinally and opened it.

7. A circuit maker and breaker constructed as set forth in claim 1, in combination with a normally-open thermostatic switch carried by the support, and interposed in the circuit to be opened and closed, the sensitivity of the switch to heat being approximately the same as that of the thermostatic elements, the switch comprising relatively-movable parts, one of which is under

the control of an operator, thereby to vary the space between said relatively-movable parts and to predetermine the time interval between the spacing of the contacts and the closing of the switch.
